UNITED STATES PATENT OFFICE.

JACOB DAVIDON, OF NEW YORK, N. Y.

ELECTRIC CAR-BRAKE.

1,238,643.

Specification of Letters Patent. Patented Aug. 28, 1917.

Application filed May 24, 1916. Serial No. 99,647.

To all whom it may concern:

Be it known that I, JACOB DAVIDON, a citizen of the United States, residing at New York, in the county of New York and State 5 of New York, have invented new and useful Improvements in Electric Car-Brakes, of which the following is a specification.

This invention relates to an electromechanical brake apparatus and has for its 10 primary object the provision of a structure capable of retarding the speed of a car in a silent manner at a minimum expenditure of energy.

An object of the invention is to provide an 15 electromechanical apparatus, the electrical devices of which are arranged in an electric circuit in such a manner that the devices will only receive current when doing work.

Besides the above my invention is distinguished in the use of an elliptical gear yieldably coöperating with an electromagnet adapted to engage the track rail.

A very important feature of my invention is the fact that the elements can be either 25 automatically operated or manually operated and the elements of all the cars of a train simultaneously operated.

With these and other objects in view the 30 invention will be better understood from the following detailed description taken in connection with the accompanying drawings, wherein

Figure 1 is a sectional view through a portion of a car showing my invention applied thereto.

Fig. 2 is a sectional view on the line 2—2 of Fig. 1.

Fig. 3 is a sectional view on the line 3—3 of Fig. 1.

Fig. 4 is a sectional view through the electromagnet.

Figs. 5 and 6 are detailed views of the mechanism, for giving movements to the frame.

Fig. 7 is a detailed sectional view through a portion of the frame.

Fig. 8 is a diagrammatic view of the wiring.

Fig. 9 is a detailed view of a modification 50 of my invention.

Fig. 10 is a side elevation of Fig. 9.

Referring to the drawings the numeral 1 designates one of the car axles having mounted thereon the flange wheels 2 each formed with inwardly extending annular series of teeth 3. At this point I wish to call

attention to the fact that the following detailed description will be limited to the brake mechanism for a single wheel, but I wish it to be understood that each wheel of 60 the car may be associated with my brake apparatus. Coöperating with the teeth 3 is the gear 4 mounted upon the axle 5 that is in turn supported by the body of the car. The axle 5 also supports a second larger gear 65 6 continuously in mesh with a smaller gear 7 upon another axle 8 also supported from the body of the car. Upon the axle 8 is an elliptical gear 9 adapted at intervals to engage a gear 10 supported in a frame 11 that 70 in turn is pivotally mounted upon the body of the car 12 as indicated at 12'. At the point where the gear 10 is supported the frame is provided with parallel limbs 13 each formed with a slot 14 for the reception 75 of the axle 8.

One end of the frame 11 supports a cylinder 15 in which is slidably mounted the head 16 of the stem 17 carried by the magnet yoke 18 that in turn supports cores 19 80 around which are wound the magnet coils 20. Encircling the stem 17 between the head 16 and end 21 of the yoke 18 is a coil expansion spring 22. From this arrangement it will be seen that the electromagnet has a 85 yieldable connection with the frame so that either the magnet or the frame may be moved independent of each other.

For the purpose of giving movements to the frame about its pivot for moving the 90 poles of the magnet into engagement or out of engagement with the tread of the rail 23 I provide a feed shaft 24 having threaded engagement with a nut 25 upon which rests the frame 11 in such a manner that the latter 95 will be prevented from swinging about its pivot except in a manner hereinafter described.

The shaft 24 carries a beveled gear 26 in mesh with a second beveled gear 27 carried 100 by the shaft 28 of the electric motor 29. The shaft 28 carries a second beveled gear 30 with which coöperates a beveled gear 31 when a shaft 32 is given a rectilinear movement by means of pressure being applied 105 upon a foot lever 33 arranged upon the platform of the car. This shaft 32 has secured thereto a wheel 33' by means of which the shaft 32 may be manually rotated for giving movement to the shaft 24 independent of the 110 motor 29.

As far as I have proceeded it will be seen

that when the motor 29 is energized, or pressure is applied to the wheel 33', the shaft 24 will be rotated and through the action of the nut 25 and threads of the shaft 24, the frame 11 will be lowered for bringing the poles of the magnet into engagement with the tread of the rail so that upon passage of current through the coils 20, the poles of the magnet will adhere to the tread of the rail. It is of course to be understood that the direction of rotation of the shaft 24 determines whether the frame 11 moves toward or away from the rail 23. Assuming that the electromagnet magnetically grips the rail each time the gear 9 makes a complete rotation, the spring 22 will be compressed twice and this compression of the spring offers great resistance to the rotation of the gear 9, and this resistance is passed from the gear 9 to the wheel 2 by means of gears 7, 6 and 4 respectively and teeth 3. Thus it will be seen that a great resistance will be offered to the turning of the wheel 2 and this is accomplished in a silent manner with the minimum amount of energy.

A feature of my invention is that as the weight of the frame portion between the pivot and magnets is much greater than the weight of the portion between the pivot and gear train, its leverage will act as a resisting force to the turning of the elliptical wheel 9 which resistance is highly increased while transmitted to the car wheel. In fact for low speeds, this force alone is sufficient to highly retard the movement of the train. Especially when a train runs on down grade or stops while being on a grade, use may be made of this braking power alone by opening switch 42 (on my original wiring sketch) after the frame has been lowered down.

Referring to the diagrammatic view of the wiring it will be seen that the coils 20 of the magnet are arranged in an electric circuit 34 including a generator 35 and a rheostat 36. Bridged across the conductor 38 and connected to conductor 37 of the circuit 34 is a conductor 39 including the motor 29 and a switch 40, the latter being arranged to be opened when the frame 11 has been lowered a distance great enough to bring the poles of the magnet into engagement with the rails, and in this particular instance the switch 40 is arranged to be struck by the nut 25. Tapped on to the conductor 38 is a conductor 41, the other terminal of which is tapped on to the conductor 39 adjacent one pole of the motor 29. This conductor 41 includes the switch 42 arranged to be closed when the nut 25 in the frame 11 moves toward the rail. Tapped on to the conductor 39 and shunted around the motor 29 and switch 42 is a conductor 43 coöperating with the conductor 41 for passing current to the mo-

tor 29 when the coils 20 are arranged inactive upon opening of the rheostat 36. The motor 29 then receives enough current to restore the frame 11 to normal position and upon the frame 11 reaching normal position the switch 42 is thrown to open position and thus preventing wastage of current. For preventing the conductors 41 and 43 from passing current to the motor 29 when the coils are active, I provide an electric magnet 44 adapted upon being energized to open a switch 45 in the conductor 43.

A very important feature of my invention is the fact that the same can be readily converted into an automatic train stop system by shunting around the rheostat 36 a conductor 46 having a two point switch 47 adapted to be struck by an obstacle in the trackway when danger conditions exist.

In the modified form of my invention, I have illustrated means for mechanically gripping the rail and in this particular instance I have shown the means associated with the electric magnet, but I wish it to be understood that the same may be used independent of the magnet and relying on the sliding friction between the means and the rail for retarding the speed of the car. In this particular instance the retarding means comprises a pair of pivot jaws 48 and 49 shaped to grip the head 50 of the rail. The shank extensions 51 and 52 of the jaws are engaged by a bracket 53 having an inclined inner surface 54 arranged to slide in contact with the shanks 51 and 52. This bracket 53 is formed integral with the frame 11.

It is to be understood that all of the several features of my improved apparatus have special coöperation with each other and together constitute a particularly effective mechanism for the purpose in view, and I therefore desire to cover the combination present in the several parts of my improved apparatus whether employed in the general organization shown or elsewhere.

What I claim is:—

1. An electromechanical brake apparatus for cars comprising a frame pivotally supported by the car for movements toward and away from the track rail, an electromagnet yieldably supported by the frame, electric means for moving said frame toward and away from the track rail, manually operated means for swinging said frame toward and away from the track rail, and an unsymmetric gear train between said frame and a wheel of the car.

2. An electromechanical brake apparatus for cars comprising a frame pivotally supported by the car for movements toward and away from the track rail, an electromagnet yieldably supported by the frame, electric means for moving said frame toward

and away from the track rail, manually operated means for swinging said frame toward and away from the track rail, and retarding means including an elliptical gear 5 arranged between said frame and one of the wheels of the car.

3. An electromechanical brake apparatus for cars comprising a frame pivotally supported by the car for movements toward 10 and away from the track rail, an electromagnet yieldably supported by the frame, electric means for moving said frame toward and away from the track rail, manually operated means for swinging said frame 15 toward and away from the track rail, and a gear train including an elliptical gear, said gear train receiving motion from one of the wheels of the car and partly supported by said frame.

20 4. An electromechanical brake apparatus for cars comprising a frame pivotally supported by the car for movements toward and away from the track rail, an electromagnet yieldably supported by the frame, electric means for moving said frame toward and away from the track rail, manually operated means for swinging said frame toward and away from the track rail, a gear train including an elliptical gear, said gear 25 train receiving motion from one of the wheels of the car and partly supported by said frame, and means supported by the electromagnet and actuated upon movement 30

of the frame and adapted to grip the track rail.

5. An electromechanical brake system comprising a swingingly mounted frame, an electromagnet supported by the frame for movements toward and away from the track rail, retarding means interposed between the 40 frame and the car wheels, means including an electric motor for giving movements to the frame, an electric circuit including a source of current, and means for interrupting the current supply to said motor upon 45 said frame reaching an abnormal position.

6. An electromechanical brake system comprising a swingingly mounted frame, an electromagnet supported by the frame for movements toward and away from the track rail, retarding means interposed between the 50 frame and the car wheels, means including an electric motor for giving movements to the frame, an electric circuit including a source of current, means for interrupting 55 the current supply to said motor upon said frame reaching an abnormal position, and means operating upon the deenergization of said magnet for reenergizing said motor for throwing the frame into its normal position. 60

In testimony whereof I affix my signature.

JACOB DAVIDON.
